UNITED STATES PATENT OFFICE.

CHARLES K. DUNLAP, OF HARTSVILLE, SOUTH CAROLINA, ASSIGNOR TO SONOCO PRODUCTS COMPANY, OF HARTSVILLE, SOUTH CAROLINA, A CORPORATION OF SOUTH CAROLINA.

DOUBLE-TAPER CONE.

Application filed March 23, 1925. Serial No. 17,735.

This invention relates to cop cones as used in the textile industry and more particularly to double taper cop cones such as described in the patent to John O. McKean 1,391,961, Sept, 27, 1921.

It is a general object of the present invention to provide a novel and improved form of double taper cop cone.

More particularly it is an object of this invention to provide a double taper cop cone having a roughened or corrugated surface throughout its length.

Another object of the present invention consists in the provision of means for providing the steeper taper of the cone with a roughened surface.

A further object of the present invention consists in the provision of means for reinforcing the steeper taper of the cone.

In the accompanying drawing and following specification there is disclosed by way of example only, a single embodiment of the present invention with the understanding however that various changes in the size, shape, arrangement and proportions of the various parts may be made without departing from the spirit of the invention as set forth in the accompanying claims.

In said drawing:

Fig. 1 is an elevation of an improved double taper cop cone constructed in accordance with the present invention; and

Fig. 2 is a longitudinal section through the same.

In the McKean Patent 1,391,961 there is disclosed a double taper cop cone together with a full explanation of the advantages of such a cone and in the McKean Patent 1,443,370 there is disclosed a type of cop to be wound on such a cone, together with the advantages of this improved type of cop. In the manufacture of double taper cones, a cone is usually wound upon a mandrel having the double taper. This cone is formed from a single sheet or blank of paper and is wound in the usual manner to the less steep slope, that is, to form a cone of a single slope or taper after which the cone while still soft, due to the adhesive material in which it is soaked prior to winding, is forced into a die or against forming rolls which reduces the tip to conform to the steeper taper of the mandrel and rounds and closes the end. Cones are wound from blanks of

paper having a roughened or corrugated surface and in the operation of reducing the tip to the steeper taper this roughened or corrugated surface is smoothed out under the action of the die or rollers. It is found necessary to retain this roughened surface throughout both tapers of the cone in order to prevent slippage of the thread or yarn which is wound upon the cone in the form of a cop. Such slippage results in an improperly formed cop and may result in tangles or snarls if the slippage takes place when the yarn is unwound. The present invention provides a means for forming double taper cones and yet retaining the roughened surface throughout.

Referring to the drawings there is disclosed generally at 10 a double taper cop cone formed by winding a blank of paper into conical form. The blank is first wound into a cone having the taper indicated at 11 corresponding to the main or body portion of the cone and in its first stage assumes the shape at the tip end indicated by dotted lines 12. While the cone is still in a soft condition due to the adhesive used to hold the turns together, it is forced into a die or against rollers which conform it to the surface of the double taper mandrel and reduce its tip end 13 to the form shown in Figure 1. This removes the roughened or corrugated surface from the paper due to the pressure of the die or rollers on the soft paper.

In order to provide, therefore, a roughened surface on the reduced end having the steeper taper, a second or smaller cone having the same taper as the reduced end is formed in the usual manner. This cone has a thinner wall than the main cone and is slipped over it and joined to it by the same adhesive used in the forming of the main and auxiliary cones. In order that there may not be a break or shoulder where the taper changes along the circumference 14, as shown in Figure 1, the reduced end of the main part of the cone is compressed or squeezed down to form a shoulder 15, as shown in Figure 2, so that the reduced end of the main portion of the cone lies below the surface of the portion 11 a distance equivalent to the thickness of the auxiliary or tip cone so that when this tip cone is placed in position, its surface conforms to

the surface of the portion 11 of the main cone and no break in the continuity of the surface is evident.

When reducing the tip of the main portion of the cone, the end is rounded as shown at 16 and the auxiliary cone is also provided with such a roughened end. The auxiliary cone not being subjected to any considerable pressure or distortion in its forming, retains the initial roughness or corrugations of the paper or blank from which it is formed and therefore its surface corresponds to the surface 11 of the main cone.

It will be seen that when reducing the tip of the main cone by compressing and distorting the paper, that the end will be weakened due to its distortion but by providing the auxiliary tip portion which is securely fastened to the main cone by adhesive, this weakened tip is reinforced and made to be even stronger than the body of the main cone, which is of considerable importance since the tip is subjected to more abuse than the other portions of the cone.

Having thus described the invention what is claimed as new and desired to be secured by Letters Patent is:

1. In a double taper cop cone of the class described, in combination, a tapered main body portion, a tip portion having a steeper taper and a reinforcing means on said tip portion, both of said portions being adapted to receive yarn.

2. In a double taper cop cone of the class described, in combination, a tapered body portion, a tip portion having a steeper taper, and a reinforcing means on the tip portion having a roughened surface.

3. In a double taper cop cone of the class described, in combination, a main cone having a tapered base portion and a tip portion of a steeper taper, said tip portion having its surface below the surface of the main portion and an auxiliary cone fitting over and secured to said tip portion and having its surface contiguous with the surface of the main portion, both of said portions being adapted to receive yarn.

4. In a double taper cop cone of the class described, in combination, a tapered main body portion, an integral tip portion having a steeper taper and means covering said tip portion and provided with a roughened surface.

5. In a double taper cop cone of the class described, in combination, a tapered main body portion formed of paper-like material, an integral tip portion having a steeper taper, the surface of said tip portion being below the surface of the main portion, and an auxiliary cone of the same material covering said tip portion, both of said portions being adapted to receive yarn.

6. In a double taper cop cone of the class described, in combination, a tapered main body portion, an integral tip portion having a steeper taper and forming a shoulder at the junction of the two tapers, and a supplemental cone covering said tip portion and having its surface contiguous with the surface of the main body portion, both of said portions being adapted to receive yarn.

In testimony whereof I hereunto affix my signature.

CHARLES K. DUNLAP.
